UNITED STATES PATENT OFFICE

2,453,856

LIQUID DISPENSING DEVICE

Fred W. Opitz, Chicago, Ill.

Application June 14, 1945, Serial No. 599,359

5 Claims. (Cl. 215—3)

1

The present invention relates generally to liquid dispensing valves, but more particularly to a simple and compact device which ejects the liquid on the outward stroke of a spring actuated plunger.

A further object of the invention is to provide a simple and improved liquid dispensing attachment for a small bottle for dispensing such liquids as hand lotion and the like whereby the bottle may be held in inverted position in one hand so that the index finger of the same hand is free to manipulate the plunger.

A further object of the invention is to provide a novel and improved as well as simplified construction of liquid dispensing attachment for a bottle where upon the repeated reciprocation of the piston and the return of the bottle to its normal vertical position, a vacuum will be created in the neck of the bottle so that the same will siphon back any liquid remaining in the discharge outlet and thereby leave the discharge duct clean and free for future use.

These and other objects are accomplished by providing a construction and an arrangement of the various parts in the manner hereinafter described and particularly pointed out in the appended claims.

Referring to the drawings:

Fig. 1 is a side elevational view showing the manner in which the bottle is tilted for dispensing the liquid therefrom with my improved liquid dispensing attachment connected thereto;

Fig. 2 is an enlarged top plan view of the same;

Fig. 3 is an enlarged vertical cross sectional view taken on the lines 3—3 in Fig. 2; and

Fig. 4 is a similar enlarged view showing the plunger compressed preparatory to ejecting a charge of liquid therefrom.

In illustrating one form of my invention I have shown the same in connection with a conventional type of small bottle 10 containing, for example, hand lotion, which has mounted on the threaded neck of the bottle, my improved form of liquid dispensing valve generally indicated by the reference character 11. The dispensing piston in this instance comprises a substantially cylindrical casing 12 which has a lower enlarged internally threaded collar portion 13, which provides the means for securing the same to the threaded neck of the bottle 10. Formed integrally with the casing 12 and located inside the internally threaded collar 13 is an annular sleeve 14, which forms in effect a liquid and piston chamber 15. The bottom of the chamber 15 forms a flat seat 16 for a disc-like plunger or piston member 17. The pis-

2

ton member 17 is secured to a plunger or piston rod 18. The other end of the plunger rod 18 has secured thereto by threaded engagement therewith a thimble-like cap 19. The cap 19 is telescopically and reciprocally mounted in a cylindrical bore or spring chamber 20 formed in the longitudinal center of the casing 12. The plunger rod 18 extends through an aperture 21 formed in the valve seat 16. Surrounding the aperture 21 is a beveled surface 22 on which is seated complementary fitting packing washer 23. Resting on the packing washer 23 is one end of a compression spring 24. The spring 24 surrounds the plunger rod 18 and has its other end seated in the bottom of the cylindrical recess 25 of the plunger cap 19. Formed integrally with the casing and projecting at an angle with respect thereto is a discharge nipple 26. Extending through the nipple and communicating with the valve chamber 15 is an outlet duct or port 27 through which the liquid is discharged on the spring-actuated return stroke of the plunger. It will be noted that the discharge duct or outlet port communicates with the liquid chamber 15 at a point below the piston member 17 when the piston member is seated on its seat 16 as shown in Fig. 3 of the drawings. This arrangement obviously permits the partial vacuum created in the bottle to siphon the liquid out of the outlet duct 27 so that it is kept clean and free for future use.

Summarizing the advantages and functions of operation of my improved liquid dispensing piston, it will, of course, be understood that by tilting the bottle angularly to the position shown in Figs. 1 or 4 of the drawings, the liquid in the bottle will flow into the neck thereof and into the piston chamber 15, so that when the plunger is depressed by the forefinger to the full-line position shown in Fig. 4 of the drawings, the liquid will flow into the chamber 15 below the disc-like piston member 17 and upon releasing the pressure on the cap 19 or plunger, the spring 24 will actuate the plunger outwardly and trapped liquid below the piston member 17 and within the piston chamber 15 will be forced out through the outlet port 27 of the nipple 26. Upon repeating the reciprocation of the plunger, additional amounts may be discharged from the nipple. In this connection it will be noted that on each occasion that the piston member is depressed inwardly, it creates in effect a suction in the outlet duct 27 to draw the liquid therein as well as the air for the next succeeding charge. In other words, this action creates in effect a partial vacuum in the bottle so that on returning the bottle to its nor-

mal vertical position, the duct 27 is clear of liquid, leaving the same clean and free for future use.

While in the above specification I have described one embodiment which may invention may assume in practice, it will, of course, be understood that the same is capable of modification and that modification may be made without departing from the spirit and scope of the invention as expressed in the following claims.

What I claim as my invention and desire to secure by Letters Patent is:

1. A liquid dispensing device comprising a casing adapted to be mounted in threaded engagement with a bottle, said casing having a piston chamber and a spring chamber, a seat formed in said piston chamber, a plunger rod extending from said spring chamber into said piston chamber, a discharge nipple carried by said casing having an outlet duct communicating with said piston chamber, a disc-like member mounted on the inner end of said plunger rod and normally seated on the seat in said chamber, the inner end of said outlet duct communicating with said piston chamber at a point spaced from the seat of said piston member and normally in communication with said piston chamber, and a spring mounted in said spring chamber and surrounding said plunger rod for actuating said disc-like member outwardly to discharge the liquid therefrom.

2. A liquid dispensing device comprising a casing, a reciprocable plunger mounted in said casing, said casing having a piston chamber therein, a disc-like piston member carried by said plunger and reciprocable in said piston chamber, said casing having an outlet duct therein communicating with said piston chamber at a point below the normal position of said disc-like piston member for normally retaining communication between said outlet duct and said piston chamber, and a spring mounted in said casing and engageable with said plunger for actuating said disc-like member to discharge the liquid through said duct.

3. A liquid dispensing device comprising a casing, a reciprocable plunger mounted in said casing, said casing having a piston chamber therein, a disc-like piston member carried by said plunger and reciprocable in said piston chamber, said casing having an outlet duct therein communicating with said piston chamber at a point below the normal position of said disc-like valve member, a depressible cap carried by said plunger reciprocally mounted in said casing, and a spring surrounding said plunger and engageable with

said cap for actuating said disc-like member to discharge the liquid through said duct.

4. A liquid dispensing device comprising a cylindrical casing having axially positioned and oppositely extending piston and spring chambers therein, there being an opening extending between said chambers, a reciprocable plunger mounted in said casing and extending through said opening, a disc-like piston member carried by said plunger and reciprocable in said piston chamber, there being an outlet duct through said casing from said piston chamber, said outlet duct normally communicating with said piston chamber, and a spring mounted in said spring chamber and engaging said plunger for actuating said disc-like member to discharge the liquid through said outlet duct.

5. A liquid dispensing device comprising a cylindrical casing having axially positioned and oppositely extending piston and spring chambers therein, a partition wall between said chambers having an opening therein, a reciprocable plunger mounted in said casing and extending through said opening, a disc-like piston member carried by said plunger and reciprocable in said piston chamber, there being an outlet duct through said casing from said piston chamber, said outlet duct communicating with said piston chamber when said disc-like piston member is normally seated, a reciprocable cap mounted on said casing and secured to the outer end of said plunger, a spring mounted in said spring chamber and engaging said cap for normally actuating said plunger and disc-like member outwardly to discharge liquid through said outlet duct.
